ATTORNEYS

UNITED STATES PATENT OFFICE.

JOHN SCHROEDER, OF DAVENPORT, IOWA.

MOTOR.

1,351,695.

Specification of Letters Patent. Patented Aug. 31, 1920.

Application filed January 31, 1920. Serial No. 355,390.

To all whom it may concern:

Be it known that I, JOHN SCHROEDER, a citizen of the United States, and a resident of the city of Davenport, in the county of Scott and State of Iowa, have invented a new and Improved Motor, of which the following is a full, clear, and exact description.

This invention relates to improvements in motors, and more particularly to motors of the character disclosed in Patent No. 873,619 granted to me December 10th, 1907, and in Patent No. 908,890 granted to me January 5th, 1909, an object of the invention being to provide improved valve operating mechanism operated by the piston rod of the motor.

A further object is to provide a valve operating mechanism which is quick operating and which most efficiently performs the functions for which it is intended.

With these and other objects in view, the invention consists in certain novel features of construction and combinations and arrangements of parts as will be more fully hereinafter described and pointed out in the claims.

In the accompanying drawings:

Figure 1 is a view in elevation illustrating my improved motor applied to a washing machine.

Fig. 2 is a view in end elevation.

Fig. 3 is a top plan elevation.

Fig. 4 is an enlarged view in vertical longitudinal section through the motor cylinder.

Fig. 5 is a fragmentary view similar to the left hand end portion of Fig. 4 showing the valve in reversed position.

Fig. 6 is a view in longitudinal section through the valve casing showing the valve in elevation.

Fig. 7 is a view in elevation of the valve.

I have illustrated my improved motor as applied to a washing machine although it is obviously capable of many other uses.

1 represents the casing of the washing machine, having an agitator shaft 2 projecting through its top 4 and the latter is provided with a stuffing box 3 to render the same water tight.

50 A motor bed 5 is secured on the top 4 and provided at one end with a post 6 to which the head 7 of a motor cylinder 8 is pivotally connected. A reciprocating piston 9 is lo-

cated in the cylinder 8 and ports 10 and 11 are provided in the cylinder heads 7 and 12 at the ends of the cylinder.

The head 7 has a conical bore forming a chamber 13 for a conical rotary plug valve 14.

The port 10 communicates directly with the valve chamber 13 and a passage 15 is provided longitudinally of the cylinder 8 connecting the port 11 with the valve casing.

The valve 14 is made with recesses 16 and 17 in opposite sides and the said recess 17 communicates with an outlet passage 18 extending to the end of the valve and communicating with a cup 19 screwed onto the end of the valve casing and provided with a discharge nipple 20 for the attachment of a hose (not shown) for conveying the exhaust to any convenient point of escape.

An inlet or supply pipe 21 discharges into the valve casing through a port 22 registering with the recess 16 and a cock 23 is provided in the pipe 21 to control the flow of water, or other motive fluid.

The stem 24 of the valve 14 is projected through a stuffing box 25 and a coiled spring 26 is located around the stem and exerts sufficient pressure on the valve to maintain the valve in operative position.

The piston rod 9' which is reciprocated by the piston 9 is secured to a rack 27, the latter guided in its movement by a bracket 27' on the engine bed 5.

The rack 27 meshes with a pinion 28 fixed to shaft 2, above the pinion 28 and is provided with an upwardly projecting crank pin 30. A coiled spring 31 connects the crank pin 30 with a vertical post 32 on the bed 5 and a rod 33 is also pivotally connected to the crank pin 30 and is longitudinally movable through an opening 34 in the post 32. A coiled spring 35 appreciably weaker than spring 31 is located around the rod 33 between the post 32 and a fixed but adjustable collar 35' on the rod to cushion the movement of the crank pin 30 and disk 29 imparted by the spring 31.

A crank arm 36 is provided on disk 29 and a rod 37 is pivotally connected to said crank arm 36.

The valve stem 24 provided on its outer end with a crank arm 38 supporting a perforated rotary pin 39, the latter receiving the rod 37 and adjustable collars 40 are se-

cured on the rod 36 and spaced apart at opposite sides of the pin to give the necessary lost motion to the rod.

The disk 29 is made with a segmental hub 41 which is engaged by a crank pin 42 on shaft 2 to move the same as will now be described.

The operation is as follows:

With the parts as shown in the drawings 10 the piston 9 and rod 9' are just beginning their movement toward the left. The rack 27 will turn pinion 28 and impart motion to the shaft 2. The disk 29 will remain stationary until the crank pin 42 engages 15 the end of hub segment 41 when it will turn the same, expanding spring 31. Just as the piston reaches the end of its stroke, the crank pin 30 will be carried past the center line of post 32 and shaft 2, and the spring 20 31 will contract, imparting a quick partial turning movement to the disk 29 and in so doing will cause the rod 37 to move the crank arm 38 to reverse the valve 14. The collars 40 being spaced apart permit the 25 initial turning movement of the disk to move the rod 37 without operating the valve as the valve is moved only by the spring 31.

Various slight changes might be made in the general form of the parts described 30 without departing from my invention, and hence I do not limit myself to the precise details set forth, but consider myself at liberty to make such slight changes and alterations as fairly fall within the spirit and 35 scope of the appended claims.

I claim:

1. A valve gear, comprising a shaft, means for turning the shaft in opposite directions, a crank disk loose on said shaft, means on 40 the shaft and disk compelling the disk to turn with the shaft during a portion of the rotary movements of the shaft in both directions, a spring operatively connected to the disk and compelling the latter to complete 45 its movements in both directions, a valve operating crank arm, and a rod connecting the disk and crank arm.

2. A valve gear, comprising a shaft, means for turning the shaft in opposite directions, 50 a crank disk loose on said shaft, means on the shaft and disk compelling the disk to turn with the shaft during a portion of the rotary movements of the shaft in both directions, a spring operatively connected to the 55 disk and compelling the latter to complete its movements in both directions, a valve operating crank arm, a rod connecting the disk and crank arm, and a second spring cushioning the movements of the crank disk 60 in both directions.

3. A valve gear, comprising a shaft, means for turning the shaft in opposite directions, a crank disk loose on said shaft, means on

the shaft and disk compelling the disk to turn with the shaft during a portion of the 65 rotary movements of the shaft in both directions, a spring operatively connected to the disk and compelling the latter to complete its movements in both directions, a valve operating crank arm, a rod connecting the 70 disk and crank arm, a second spring cushioning the movements of the crank disk in both directions, and a single crank pin on the crank disk operatively connected to both of the springs. 75

4. A valve gear, comprising a shaft, means for turning the shaft in opposite directions, a crank disk loose on the shaft, a segmental hub on the crank disk, a pin on the shaft engaging the ends of the segmental hub and 80 compelling the disk to turn with the shaft during portions of the rotary movements of the shaft in both directions, a fixed post having an opening therein, a crank pin on the disk, a rod connected to the crank pin 85 and extending through the opening in the post, a spring on the rod located between the post and a fixed part of the rod and cushioning the movement of the crank pin, a second spring connecting the crank pin and 90 post and positioned tangentially to the disk so as to complete the movements of the crank disk in both directions after said movement is initiated by the shaft, a valve operating crank arm, and a rod connected 95 at one end to the crank disk and at its other end having a loose connection with the crank arm, said loose connection permitting a predetermined movement of the rod before moving the crank arm. 100

5. A valve gear, comprising a shaft, means for turning the shaft in opposite directions, a crank disk loose on the shaft, a segmental hub on the crank disk, a pin on the shaft engaging the ends of the segmental hub 105 and compelling the disk to turn with the shaft during portions of the rotary movements of the shaft in both directions, a fixed post having an opening therein, a crank pin on the disk, a rod connected to the crank 110 pin and extending through the opening in the post, a spring on the rod located between the post and a fixed part of the rod and cushioning the movement of the crank pin, a second spring connecting the crank pin and post and positioned tangentially to the disk so as to complete the movements of the crank disk in both directions after said movement is initiated by the shaft, a valve operating crank arm, and a rod connected 115 at one end to the crank disk and at its other end having a loose connection with the crank arm, said loose connection permitting a predetermined movement of the rod before moving the crank arm.

JOHN SCHROEDER.
